UNITED STATES PATENT OFFICE.

THOMAS H. SEELY, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

1,324,985.

Specification of Letters Patent.

Patented Dec. 16, 1919.

Original application filed January 29, 1914, Serial No. 815,127. Divided and this application filed January 3, 1916. Serial No. 69,968.

To all whom it may concern:

Be it known that I, THOMAS H. SEELY, a citizen of the United States, residing at Dorchester, Boston, in the county of Suffolk 5 and Commonwealth of Massachusetts, have invented certain new and useful Improvements in Shoe-Sewing Machines; and I do hereby declare the following to be a full, clear, and exact description of the invention 10, such as will enable others skilled in the art to which it appertains to make and use the same.

This invention relates to wax thread sewing machines, and more particularly to 15 thread gripping devices for such machines.

The object of the invention is to improve the construction, arrangement and mode of operation of thread gripping devices for holding, during the beginning of each seam 20 formation, the free end of thread projecting from the thread handling devices.

With this object in view the invention consists in the novel and improved construction and arrangement of parts hereinafter 25 described and particularly pointed out in the claims, the advantages of which will be obvious to those skilled in the art.

The invention will be readily understood from an inspection of the accompanying 30 drawings illustrating the preferred embodiment of the invention and the following detailed description thereof.

In the drawings, Figure 1 is a view in side elevation of a portion of a shoe sewing machine embodying the invention; Fig. 2 is a detail view illustrating particularly the looper and the thread gripping and thread cutting devices mounted on the looper arm, looking in the direction of the arrow *a*, Fig. 40 1; and Fig. 3 is a detail view illustrating the parts shown in Fig. 2, looking in the direction of the arrow *b*, Fig. 1.

The machine embodying the invention as illustrated in the drawings is a shoe sewing 45 machine of the class employing a curved hook needle and devices co-operating therewith to form a chain stitch seam, and is particularly designed for sewing inseams of welted and turn shoes. The curved hook 50 needle 2, the thread finger 4, the looper 6, and the channel guide 6^a all have the same construction and are arranged to operate in the same manner as the corresponding parts of the machine illustrated in applicant's

Patent No. 1,240,094, dated September 11, 55 1917, granted on application, Serial No. 815,127, filed January 29, 1914, of which the present application is a division. As fully described in said patent, the looper is secured to the lower end of a lever 3, 60 pivotally mounted on a longitudinally fixed hollow shaft 5 supported by the forward end of the reciprocating slide 7. The hollow shaft is supplied with steam through an inlet pipe 9, and the steam passes therefrom 65 through an outlet pipe 11.

The thread gripping device for holding the free end of the thread during the beginning of a seam formation is secured to the arm 8 upon which the looper is mounted 70 and comprises clamping plates 10 and 12 secured together by screws 14 and provided respectively with diverging clamping jaws 16 and 18 between which the thread is inserted by the operator in removing a shoe 75 from the machine. The thread is held frictionally between the jaws of the gripping device with sufficient force to maintain the proper tension on the thread and at the same time to allow the thread to slip under 80 the strain exerted thereon by the thread handling devices during the formation of the first stitch. To enable the thread to be severed readily between the sewing mechanism and the work when a seam has been 85 completed, a thread cutting knife 20 is clamped to the outer face of the clamping plate 12, and is provided with a cutting blade at its left-hand edge, Fig. 2, across which the thread is drawn by a suitable 90 movement of the shoe to sever the thread. As will be noted from an inspection of Figs. 2 and 3, the cutting blade of the thread cutting knife is located at some distance from the jaws of the gripping device so that a 95 considerable length of free thread is left projecting from the gripping device after the thread is severed.

It is undesirable that the thread gripping device should be heated to a high temperature during the operation of the machine, since when this device is kept hot it will not hold the waxed thread in a reliable manner and maintain the proper tension upon the same during the formation of the first stitch. 100 In the construction illustrated, the thread gripping device is secured to the outer end of an arm 22 extending outwardly from the

looper arm, as shown in Fig. 2, by means of a screw 24 passing through a slot in a projection or lug on the clamping plate 10 and screwed into the arm 22. With this construction the thread gripping device is spaced from the looper arm and is, therefore, maintained at a low temperature relative to that of the looper.

- To enable the thread clamping jaws to be 10 relatively adjusted to suit the different sizes of thread and to regulate the tension applied to the thread during the formation of the first stitch, the clamping plate 12 is provided on the side thereof adjacent the plate 10 15 with angularly arranged faces 26 and 28, the plate 12 engaging the plate 10 at the meeting point of these faces so that it may be rocked about this point to regulate the opening between the thread clamping jaws. The 20 clamping plate 12 is adjusted about its point of engagement with the plate 10 by a suitable adjustment of the screws 14.

When a seam has been completed, the operator, as he removes the shoe from the 25 machine, manipulates the shoe to place the thread leading from the machine to the work between the jaws 16 and 18 of the gripping device and to draw the thread across the cutting blade of the knife 20 to 30 sever the same. As a new seam is started, the free end portion of the thread which is held by the gripping device may slip forward through the thread gripping jaws under the strain exerted on the thread by the 35 thread handling devices. The length of thread projecting beyond the gripping device, however, is such that the thread is not drawn out of the gripping jaws during the formation of the first stitch, but is still held 40 under tension after the first stitch is completed.

The present construction of the gripping device enables the jaws thereof readily to be 45 relatively adjusted for any size of thread to give the proper tension for the tightening of the first stitch.

Having explained the nature and object 50 of the present invention, and having specifically described a machine embodying the same in its preferred form, what is claimed is:

1. A shoe sewing machine having, in com-

bination, stitch forming devices, a thread clamp for holding the free end of the thread at the beginning of the formation of a seam 55 comprising clamping plates provided with opposed thread clamping jaws normally having a stationary relation to each other during each cycle of operations, and means whereby one of said plates may be adjusted 60 angularly with relation to the other to vary the opening between the jaws.

2. A shoe sewing machine having, in combination, stitch forming devices, a thread clamp for holding the free end of the thread 65 at the beginning of the formation of a seam comprising clamping plates provided with opposed thread clamping jaws normally having a stationary relation to each other during each cycle of operations, one of said 70 plates having angularly disposed faces and engaging the other plate at the meeting point of these faces, and adjustable devices arranged on the opposite sides of the point of contact of said plates for securing the 75 plates together, whereby one of the plates may be adjusted angularly with relation to the other to vary the opening between the jaws.

3. A wax thread sewing machine having, 80 in combination, stitch forming devices comprising a looper, means for heating the looper, an arm secured to the looper and extending outwardly therefrom, and a thread clamp for holding the free end of the thread 85 mounted on the outer end of said arm, whereby the thread clamp is maintained at a low temperature relative to that of the looper.

4. A shoe sewing machine, having, in combination, stitch forming devices, a thread clamp for holding the free end of the thread at the beginning of the formation of a seam, comprising clamping plates provided with opposed thread-clamping jaws normally 95 having a stationary relation to each other, during each cycle of operations, one of said plates having angularly disposed faces and engaging the other plate at the meeting point of these faces, and means whereby one 100 of the plates may be adjusted angularly about the point of contact of said plates to vary the opening between the jaws.

THOMAS H. SEELY.
